UNITED STATES PATENT OFFICE.

WILLIAM LOGAN, OF AUCKLAND, NEW ZEALAND.

CAMERA-SIGHTER.

1,359,515.

Specification of Letters Patent. Patented Nov. 23, 1920.

Application filed January 27, 1920. Serial No. 354,431.

To all whom it may concern:

Be it known that I, WILLIAM LOGAN, of the city of Auckland, in the Provincial District of Auckland, in the Dominion of New Zealand, a subject of the King of Great Britain and Ireland, have invented certain new and useful Improvements in Improved Camera-Sighters, of which the following is a specification.

10 This invention relates to means employed in sighting cameras on to objects it is desired to photograph.

The object of the invention is to provide an improved device, the use of which enables 15 cameras whether held stationary, or movable to be quickly and accurately sighted on to objects either stationary or movable.

According to the invention the device hereinafter referred to as a holder is shaped 20 somewhat similarly to a gun and is provided with fore and back sights.

At a point on the holder corresponding to the forward end of the stock of a gun, an 25 upper inverted cross recess and a lower cross recess are provided, the lower cross recess being made in a detachable portion adapted to be secured to the lower edge of the holder at a distance from the upper cross recess.

A camera pointing in the same direction 30 as the forward portion of the holder is clamped between the detachable portion and the portion to which the latter is secured, and when properly adjusted is capable of photographing an object viewed through the 35 sights of the holder, the latter being used preferably by being brought to the shoulder in the same manner as a gun, although it can be used otherwise.

The camera shutter is operated by the 40 usual cable attached to the holder in a convenient position.

The holder is also preferably hinged so as to be capable of being folded when not in use.

45 Referring to the drawings accompanying this specification and in conjunction with which the invention will be more particularly described:—

Figure 1 is a side elevation, and

50 Fig. 2 a plan view of the device, while Fig. 3 is a side elevation of same folded and

Figs. 4 and 5 are enlarged part side views

showing convenient ways of attaching the cable.

The holder 1 is given the shape of a gun and is provided with sights 2 similarly to the latter.

The detachable part 3 is secured to the lower edge of the holder, by means of a 60 screw and wing nut 4 and a stud 5, in a position corresponding to the front end of a gun stock.

A cross recess 6 is provided in the detachable portion 3 and an inverted cross recess 65 7 is made in the upper portion of the holder directly over the recess 6.

The holder 1 is hinged at 8 so that it can be folded (Fig. 3) when required, and has a pivoted bar 9 fixed to one portion, said bar 70 9 having a slot 10 at its free end adapted to engage a screw 11 on the other portion when the device is opened out for the purpose of insuring the rigidity of the device during use.

75 The camera 12 rests on the detachable portion 3 and fits in the recesses 6, 7, so that by tightening the wing nut, it is caused to be securely clamped to the holder 1 in such a position that when an object is viewed 80 through the sights 2, the camera is also accurately sighted on the same object.

In order to provide a greater surface for the back of the camera 12 to bear against, and so prevent movement of the latter in the 85 holder 1, one or more projections or extensions 1^a are provided on the sides of the holder.

The simplest way of using the holder 1 is to bring it to the shoulder similarly to a gun, 90 but it can also be used by being placed on any suitable support.

The cable 13 from the camera 12 for operating the shutter, is fitted with the usual spring push 14 at the end.

95 The end of the cable 13 with the spring push 14 is preferably attached to the holder at the waist of the latter.

One way of attaching and operating the spring push 14, is to secure the cable end in 100 a spring clip 15, so that when a trigger 16 (Fig. 4) is pulled in the direction indicated the spring push 14 is pressed into the cable 13.

Another way is to secure the end of the 105 cable 13 to the holder 1 by means of clip 17

(Fig. 5) with the spring push 14 pointing toward the forward end of the holder, and in the latter case the spring push 14 is operated in the direction indicated by the 5 finger of the user of the holder.

What I do claim and desire to secure by Letters Patent of the United States is:—

1. A camera holder and sighter, having an upper inverted cross recess therein; and 10 a foresight and a back sight thereon; and a lower detachable portion with a cross recess therein directly below said inverted cross recess; and between which and the holder proper a camera is adapted to be 15 secured.

2. A camera holder and sighter in two portions hinged together; and having a plate pivoted to one of said hinged portions and slotted to engage a screw on the other 20 of said hinged portions; an inverted cross recess in said holder, and a foresight, a back sight and side projections thereon; a lower detachable portion with a cross recess directly below said inverted recess and be- 25 tween which and the holder proper a camera is adapted to be secured.

3. A camera holder and sighter in two portions hinged together; and having, a

slotted plate pivoted to one of said hinged portions so as to engage a screw on the other 30 of said hinged portions; an inverted cross recess in said holder, and a foresight, a back sight and side projections thereon; a lower detachable portion with a cross recess directly below said inverted cross recess; and 35 a spring clip on said holder for attaching the end of the camera cable to the latter.

4. A camera holder and sighter in two portions hinged together, and having a slotted plate pivoted to one of said hinged portions so as to engage a screw on the other 40 of said hinged portions; an inverted cross recess in said holder, and a foresight, a back sight and side projections thereon; a lower detachable portion with a cross recess directly below said inverted recess, and a 45 spring clip and a trigger for attaching the end of the camera cable to the holder and for operating the spring push in said cable respectively.

In testimony whereof I affix my signature in the presence of two witnesses.

WILLIAM LOGAN.

Witnesses:

WILLIAM PINCHES,
ELSA GREENE.
